UNITED STATES PATENT OFFICE.

OTTO F. FOGELSTRAND, OF KENSINGTON, CONNECTICUT, ASSIGNOR TO HART,
BLIVEN & MEAD MANUFACTURING COMPANY, OF SAME PLACE.

DESIGN FOR DRAWER-PULL.

Specification forming part of Design No. 6,775, dated July 15, 1873; application filed June 30, 1873.

To all whom it may concern:

Be it known that I, OTTO F. FOGELSTRAND, of Kensington, in the county of Hartford and State of Connecticut, have invented and produced a new and original Design for a Drawer-Pull, of which the following is a specification:

The nature of my design is fully represented by the accompanying engraving, to which reference is made.

The ends and top of the pull proper A form five sides, with an ornamental flange or base, B, at their upper sides, and star-shaped wings C C at the ends, which wings are provided with screw-holes for securing the device in place.

The surface of the pull proper is ornamental work in relief, and it and the base B have numerous ornamental perforations, as shown.

I claim as my invention—

1. The design for the wings C C of a drawer-pull, substantially as shown.
2. The design for the base B of a drawer-pull, substantially as shown.
3. The design for the pull proper A, substantially as shown.

OTTO F. FOGELSTRAND.
